UNITED STATES PATENT OFFICE.

GEORGE H. EGBERS, OF CINCINNATI, OHIO.

DEVICE FOR RAISING OR LOWERING AWNINGS.

SPECIFICATION forming part of Letters Patent No. 705,744, dated July 29, 1902.

Application filed March 31, 1902. Serial No. 100,673. (No model.)

To all whom it may concern:

Be it known that I, GEORGE H. EGBERS, a citizen of the United States, residing at Cincinnati, in the county of Hamilton and State of Ohio, have invented certain new and useful Improvements in Devices for Raising or Lowering Awnings, of which the following is a specification.

My invention relates to an improvement in means for manipulating awnings; and the object of the invention is to provide the parts of great simplicity, strength, and durability and so located in a housing as to be concealed and yet readily accessible to operation.

15 The features of my invention are more fully set forth in the description of the accompanying drawings, forming a part of this specification, in which—

Figure 1 is an end elevation of my improvement with the housing-cap removed. Fig. 2 is a side elevation of Fig. 1. Fig. 3 is an end view of the housing and cap in position. Fig. 4 is a front elevation of the housings and projecting parts. Fig. 5 is a perspective view of 25 the housing-cap.

A represents a wall of a building.

B represents the base of the case or housing, which is rigidly anchored to the wall by screw-bolts a.

30 C represents a casing or housing rigidly secured to the base-piece B.

D represents the driving-shaft. It is journaled in the base B and the outer side wall of the shell C of the case.

35 E represents a vertical transmitting-shaft projecting up parallel with the wall of the building, its lower end journaled in the end wall d of the casing. The upper end of said shaft journals in the bracket e, which is securely anchored to the wall of the building.

F represents a bevel-gear on shaft D.

G represents a bevel-gear on the lower end of shaft E.

I represents the roller on which the awning-canvas is wound.

45 J represents the bevel-gear secured to the end of the roller I, meshing with and driven by the bevel-gear H.

K represents a ratchet-wheel secured to 50 shaft D.

L represents a lock-lever pivoted to the upper edge of the casing C. This is provided

with a tooth g, adapted to engage serially with the teeth h of the ratchet-wheel. The shape of the teeth g and h is such that when 55 the awning-roller is wound up these teeth come into locking engagement and hold the awning from unwinding.

m represents a locking and tripping arm rigidly fixed to the pawl-lever L. It projects 60 outward through the slot i of the casing-cap C'. The outer end of this stem is provided with an eye. Upon the casing-cap is mounted a rigid ear n, likewise having an eye, which when the ratchet-lever L is in engagement with one of the ratchet-teeth h occupies the position shown in Fig. 4. This eye is in juxtaposition with the eye of the ear n, in which position they may be securely locked by the hasp O of an ordinary padlock. 70

P represents the projecting end of shaft D, squared to receive a crank, so that the said shaft may be turned.

Mode of operation: Suppose the awning to be wound up, but the padlock O removed. If 75 it is now desired to unwind the awning, the attendant applies the crank to the squared head P of the shaft. He then turns the crank toward the winding direction slightly, and he can then easily lift the ratchet-lever L by 80 taking hold of the projecting end and allowing the awning-pole to be unwound, applying sufficient power to the crank to prevent too rapid unwinding, and consequently tearing the awning from off the pole. When the 85 awning has been unwound, he releases the pawl-lever L, which may be locked in this position, if desired. To roll up the awning, the attendant simply turns the crank and the pawl-tooth automatically comes into serial 90 engagement with the ratchet-teeth h. When the awning is wound up to the desired position, the lever-stem m can be locked to the ear n and the crank removed and the awning secured against accidental unwinding. This 95 locking also prevents mischievous persons from tampering with the fixture.

Several important advantages are obtained by the construction herein described.

As the strains are on the horizontal driving-shafts and the casing is projected from the side wall, it is desirable to have the thrusts on said shaft sustained as much as possible upon the base. The said shaft D is projected

across the casing and is journaled in the base of vertical wall B, which journal is in the plane of the anchor-bolts a. It will be observed that the cap-piece of the casing and the casing have two fastening-flanges, one of which forms a bearing and cap for the shaft E and the other fastening-flange forms the bearing for the shaft D, and the two sections of the case are secured together by bolts passing through said flange-bearings upon each side of the respective shafts, thus making a rigid union of the casings and a firm bearing-support for the shafts, which being at right angles with each other have a tendency to strain the casings at the joints. The construction therefore is simple, allowing convenient access for the taking down and putting up of awning devices by taking the case apart, which when put together is made strong and durable by the construction herein shown and described.

Having described my invention, what I claim, and desire to secure by Letters Patent, is—

25 1. A device for operating awnings consisting of a casing made in two sections, a base B formed integral with one of said sections,

a driving-shaft D journaled to said base and casing provided with a bevel-gear F, a driven shaft journaled in said casing, a bevel-gear 30 on said shaft meshing with the bevel-gear on the driving-shaft, fastening-flanges on said casing which form the bearings of the said shafts, and fastening-bolts fastening through said flanges upon each side of respective 35 shafts, substantially as specified.

2. In a device for operating awnings the combination with a casing adapted to be anchored to the walls of a building, a slotted cap for the casing, a driving-shaft and driven 40 shaft journaled in said casing, a ratchet-gear inclosed within said casing, a pawl-lever hinged within the casing and having an arm projecting through said slot in the casing-cap, a projection on the casing coincident 45 with the said projecting arm when the parts are in their position, substantially as specified.

In testimony whereof I have hereunto set my hand.

GEORGE H. EGBERS.
